(57) **ABSTRACT**

A new cultivar of *Carex* plant named 'Lunar Falls' that is characterized by its variegated foliage with wide white margins, its fast growing plant habit with a one-gallon plant produced in one season, its ease of propagation by division, and its very stable variegation with no solid white or green shoots observed.

2 Drawing Sheets

1

Botanical classification: *Carex* hybrid.
Varietal denomination: 'Lunar Falls'.

BACKGROUND OF THE INVENTION

The present invention relates to a new and distinct cultivar of *Carex* hybrid and will be referred to hereafter by its cultivar name, 'Lunar Falls'. 'Lunar Falls' is a new cultivar of perennial grown for container and landscape use.

The new cultivar was discovered by the Inventor in spring of 2020 as a naturally occurring cimeral mutation of *Carex* 'Feather Falls' (U.S. Plant Pat. No. 26,199) in a container in Zebulon, North Carolina.

Asexual propagation of the new cultivar was first accomplished by division by the Inventor in July of 2020 in Zebulon, North Carolina. Asexual propagation by division have determined that the characteristics are stable and are reproduced true to type in successive generations.

SUMMARY OF THE INVENTION

The following traits have been repeatedly observed and represent the characteristics of the new cultivar. These attributes in combination distinguish 'Lunar Falls' as a distinct cultivar of *Carex*.

1. 'Lunar Falls' exhibits variegated foliage with wide white margins.
2. 'Lunar Falls' exhibits a fast growing plant habit with a one-gallon plant produced in one season.
3. 'Lunar Falls' exhibits ease of propagation by division.
4. 'Lunar Falls' exhibits very stable variegation with no solid white or green shoots observed.

The parent plant of 'Lunar Falls' differs from 'Lunar Falls' in having thinner margins that are creamy white in color and a slower growth habit. 'Lunar Falls' can be most closely compared to *Carex* cultivars 'Everest' (U.S. Plant Pat. No. 20,955) and 'Everillo' (U.S. Plant Pat. No. 21,002). 'Everest' is similar to 'Lunar Falls' in having variegated foliage with white margins, long pendulous leaves, and a

5 'Everillo' is similar to 'Lunar Falls' in having variegated foliage, long pendulous leaves, and a clumping plant habit.

'Everillo' differs from 'Lunar Falls' in having variegated foliage with golden colored margins, less adaptability to

10 growing conditions with less drought and sun tolerance, and a smaller plant size.

2

clumping growth habit. 'Everest' differs from 'Lunar Falls' in having variegated foliage with narrower white margins, less adaptability to growing conditions with less drought and sun tolerance, a smaller plant size and slower growth habit.

15 'Everillo' is similar to 'Lunar Falls' in having variegated foliage, long pendulous leaves, and a clumping plant habit.

'Everillo' differs from 'Lunar Falls' in having variegated

5 foliage with golden colored margins, less adaptability to

10 growing conditions with less drought and sun tolerance, and a

a smaller plant size.

BRIEF DESCRIPTION OF THE DRAWINGS

15 The accompanying color photographs illustrate the overall appearance and distinct characteristics of the new *Carex*. The plant in the photographs were taken of a one-year-old plant of the new cultivar as grown outdoors in 0.5-gallon containers in Zebulon, North Carolina.

20 The photograph in FIG. 1 provides a side view of the plant of 'Lunar Falls' in bloom.

The photograph in FIG. 2 provides a close up of the inflorescences of 'Lunar Falls'.

25 The photograph in FIG. 3 provides a close up of the foliage of 'Lunar Falls'. The colors in the photographs are as close as possible with the photographic and printing technology utilized and the color values cited in the detailed botanical description accurately describe the colors of the new *Carex*.

DETAILED BOTANICAL DESCRIPTION

30 The following is a detailed description of one-year-old plants of the new cultivar as grown outdoors in 0.5-gallon containers in Zebulon, North Carolina. The phenotype of the new cultivar may vary with variations in environmental, climatic, and cultural conditions, as it has not been tested under all possible environmental conditions. The color determination is in accordance with the 2015 Colour Chart

of the Royal Horticultural Society, London, England, except where general color terms of ordinary dictionary significance are used.

General Description:

Blooming period.—2 to 3 weeks in early summer in 5
North Carolina.

Plant type.—Herbaceous perennial.

Plant habit.—Upright with arching leaves.

Growth habit.—Upright, compact, clump forming, 10
arching foliage.

Height and spread.—Average of 33 cm in height and 15
58 cm in diameter as a one-year-old plant grown in a
container, reaches 61 cm in height and 1.2 m in
spread in the landscape.

Hardiness.—At least in U.S.D.A. Zones 5 to 9.

Diseases and pests.—No susceptibility or resistance to 15
pests and diseases has been observed.

Root description.—Short, stout rhizomes with dense, 20
fibrous roots, roots moderately branched, color; a
blend of NN155D, 162C, and 176A.

Propagation.—Shoot division.

Time required for root development.—4 to 6 weeks to 25
produce a well rooted liner from a division, will fully
root in a one-gallon container in one growing season.

Shoots.—An average of 30 main shoots growing from 25
the base.

Growth rate.—High.

Foliage Description:

Leaf shape.—Linear, curved.

Leaf division.—Simple.

Leaf base.—Sheathing.

Leaf apex.—Long acuminate.

Leaf aspect.—Average angle of 30° to 40° to shoot 30
axis, leaves initially emerge upright, then cascade
outward and finally arch downward.

Leaf venation.—Parallel, not distinguishable except
main vein, color of upper and lower surface of main 35
vein 144A.

Leaf margins.—Entire, sharp to the touch when rubbed
due to very small teeth that are too small to be seen 40
or measured.

Leaf size.—Average of 50 cm in length and 7 mm in 45
width.

Leaf number.—Average of 15 leaves per shoot, 80 per
plant.

Leaf arrangement.—Alternate.

Leaf surface.—Upper and lower surface smooth, gla- 50
brous, upper surface glossy, lower surface moderately
glossy.

Leaf color.—Young and upper and lower surface;
144A, margins are thin and a blend of NN155D to
NN155A, mature upper surface; narrow center stripe
141A, wider margins NN155D to NN155A, mature
lower surface; wider center stripe 144A, narrow
margins NN155D.

Petiole.—None.

Leave sheathes.—Average of 4 cm in length, 4 mm in
width, transparent, 158B, laterally striped 200B.

Flower Description:

General description.—Terminal racemes, male and
female flowers in separate spikelets.

Inflorescence size.—Averages 13 cm in height and 5
cm in width.

Flower quantity per inflorescence.—Typically 200
male flowers placed in an average of 1 spikelet and
an average of 50 female flowers placed in an average
of 1 spikelet.

Lastingness of inflorescence.—Flowers last about 10
days.

Fragrance.—None.

Floret buds.—Ovate in shape, 1.5 cm in length and
about 3.5 mm in diameter, range from 144D in color.

Spikelet aspect.—Upright to outward.

Spikelet shape.—Sedge-like.

Persistence of spikelets.—Persistent.

Floret (spikelet) size.—Staminate florets; up to 6 cm in
length, 5 mm in diameter, pistillate florets; up to 2.5
cm in length, 1.5 cm in diameter.

Floret (spikelet) description.—1 glume on outer side
and 1 lemma on inner side on staminate florets and
1 lemma on inner side of pistillate florets, glumes; an
average of 5 mm in length and 1 mm in width,
lanceolate in shape, margin entire, apex narrowly
acute, color of upper and lower surface 142C, sur-
face is smooth and dull in appearance, lemma; an
average of 2 mm in length and .5 mm in width,
lanceolate in shape, margin entire, apex long and
mucronate, color of upper and lower surface on
staminate florets a blend of 165A and 165B, color of
upper and lower surface on pistillate florets 165B,
surface is smooth and dull, and lustrous in appear-
ance.

Peduncle.—An average of 24.5 cm in length and 4 mm
in diameter, very strong, slightly outward angle from
vertical, triangular in shape, surface is glossy and
144A in color.

Reproductive Organs:

Gynoecium.—Pistils; 3, 7 mm in length, stigmas; fimbriate, 197C in color, style; minute, 0.1 mm in
length, insufficient in size to be color coded, ovary;
157A in color.

Androecium.—Stamens; 3, basifixed, 2 mm in length,
color 164A, pollen; none observed.

Fruits and seeds.—Seed production has not been
observed to date.

It is claimed:

1. A new and distinct cultivar of *Carex* plant named
'Lunar Falls' as herein illustrated and described.
